DESIGN FOR A TELEPHONE STAND

Jean O. Reinecke, Chicago, Ill., assignor to James F. Barnes, as trustee

Application March 3, 1945, Serial No. 118,241

Term of patent 14 years

(Cl. D33—19)

To all whom it may concern:

Be it known that I, Jean O. Reinecke, a citizen of the United States, residing at Chicago, county of Cook and State of Illinois, have invented a new, original, and ornamental Design for a Telephone Stand, of which the following is a specification, reference being had to the accompanying drawing forming a part thereof, in which:

Fig. 1 is a perspective view of a telephone stand embodying the new design; Fig. 2 is a front elevational view of the same; and Fig. 3 is a side elevational view of the same.

I claim:

The ornamental design for a telephone stand, as shown.

JEAN O. REINECKE.
